(74) **Attorney, Agent, or Firm** — Andrew C. Cheng

(57) **CLAIM**

The ornamental design for a film applicator as shown and described.

DESCRIPTION

FIG. 1 is a top, front, left side perspective view of a film applicator;

FIG. 2 is a top, rear, right side perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a bottom, rear, right side perspective view thereof, showing additional broken lines depicting a phone;

FIG. 10 is a left view thereof, showing additional broken lines depicting a phone; and,

FIG. 11 is a bottom, front, left side perspective view thereof, showing additional broken lines depicting a phone.

The broken lines in the drawings depict portions of the film applicator that form no part of the claimed design. The additional broken lines in FIGS. 9-11 depict a phone representing environment that forms no part of the claimed design.

1 Claim, 11 Drawing Sheets
